UNITED STATES PATENT OFFICE.

WILLIAM C. MEYER, OF BEVERLY, MASSACHUSETTS, ASSIGNOR TO UNITED SHOE MACHINERY CORPORATION, OF PATERSON, NEW JERSEY, A CORPORATION OF NEW JERSEY.

TENSION DEVICE.

Application filed April 13, 1920. Serial No. 373,503.

To all whom it may concern:

Be it known that I, WILLIAM C. MEYER, a citizen of the United States, residing at Beverly, in the county of Essex and State 5 of Massachusetts, have invented certain new and useful Improvements in Tension Devices; and I do hereby declare the following to be a full, clear, and exact description of the invention, such as will enable others 10 skilled in the art to which it appertains to make and use the same.

This invention relates to sewing machines and, more particularly, to tension devices for such machines.

15 The objects of the invention are to improve the construction and mode of operation of tension devices and to produce a tension device of simple construction which will operate in a reliable manner to maintain 20 a substantially constant tension on the thread and having novel and improved means for releasing the tension, novel and improved means for heating the tension wheel and novel provisions for adjustment 25 of certain of the parts.

With the above objects in view, the invention comprises certain novel and improved construction arrangements and combinations of parts hereinafter described and 30 particularly pointed out in the claims, the advantages of which will be readily understood and appreciated by those skilled in the art.

The invention will be clearly understood 35 from the accompanying drawings illustrating the invention in its preferred form and the following detailed description of the constructions therein shown.

In the drawings Figure 1 is a view in side 40 elevation of a tension device embodying the invention; Fig. 2 is a view in rear elevation of the tension device; and Fig. 3 is a sectional view of the tension device taken substantially on the line 3-3 of Fig. 2.

45 The tension device illustrated in the drawing comprises a tension wheel 2 mounted on the inner end of a hollow shaft 4 and arranged so that the thread may be passed about the same on its way from the supply to the work as clearly shown in Figs. 1 and 2. The shaft 4 is rotatably mounted on a stud 6 secured at its inner end in the frame of the machine, and the rotation of the shaft is controlled to control the tension applied

to the thread by means of a brake mechanism. 55

This brake mechanism comprises a brake wheel 8 secured to the outer end of the shaft 4 and brake shoes 10 and 12 arranged to engage the peripheral surface of the brake wheel, the brake shoes having linings of felt indicated at 13 for contact with the brake wheel. The brake shoes are supported at their upper ends by means of a bolt 14 secured by a set screw 15 in a bracket 16 on the frame of the machine and passing loosely through suitable openings in the brake shoes. The upper end of the brake shoe 10 is pressed outwardly away from the bracket 16 by means of a coiled spring 18, and the movement of the brake shoe under the action of the spring is limited by means of a winged nut 20. The lower ends of the brake shoes are connected by means of a bolt 22 passed through openings in the same, and the lower ends of the shoes are pressed yielding together to cause them to engage yielding the brake wheel by means of a coiled spring 24 interposed between the brake shoe 10 and a winged nut 26 threaded on the rear 80 end of the bolt 22. The brake shoes are thus caused yielding to engage the brake wheel so as to retard frictionally the rotation thereof and apply tension to the thread.

The above manner of mounting the brake 85 shoes enables the same to be adjusted independently to compensate for wear and also to locate the same properly with relation to the brake wheel. The upper end of the brake shoe 12 may be adjusted toward and 90 from the bracket 16 by adjusting the bolt 14 in said bracket and the upper end of the brake shoe 10 may be adjusted toward and from the bracket by adjusting the nut 20 on the bolt 14. 95

To relieve the tension on the thread, the lower ends of the brake shoes are moved relatively away from each other against the action of the coiled spring 24. The mechanism for moving the lower ends of the brake 100 shoes away from each other comprises a block 28 secured to the forward end of a rock-shaft 30 mounted in a bearing in the frame, the block being arranged between the lower ends of the brake shoes as clearly 105 shown in the drawings. Upon rotating the block 28 the block engages the lower ends of the brake shoes and separates the same as

shown in Fig. 3. An operating arm 32 is secured to the outer end of the block and is provided with an opening through which is passed a longitudinally movable rod 34. By moving the rod 34 forwardly the arm 32 and block 28 may be actuated to separate the lower ends of the brake shoes. By proper adjustment of the upper ends of the brake shoes, the lower ends of the shoes may be located so that the block 28 will act uniformly on the same in disengaging the brake shoes from the brake wheel.

The heating means for the tension device comprises a steam chest 36 secured to the frame adjacent the tension wheel and having a central chamber to which steam is delivered through an inlet pipe 38. The steam passes from the chamber in the steam chest through outlet pipes 40 and 42. As a further provision for keeping the tension wheel heated to a high temperature, a circular casing 44 surrounding the tension wheel is provided. This casing is preferably formed as a part of the frame and the steam chest 36 is secured to the wall of the casing, so that the casing is kept hot by the heat received by conduction from the steam chest. The thread on its way to the casing 44 passes through a tube 46 attached at one end to the casing and after leaving the tension wheel, the thread passes through a tube 48 also connected with the casing. The casing transmits considerable heat to the tension wheel by radiation and the casing and thread tubes protect the thread from air currents which might chill the wax.

Having explained the nature and object of the invention and having specifically described a device embodying the invention in its preferred form, what is claimed is:

1. A tension device for sewing machines, having in combination, a tension wheel, a brake for the tension wheel comprising a brake wheel, a pair of brake shoes for engagement with the periphery of the brake wheel, means for pressing the brake shoes against the brake wheel, and means for supporting the brake shoes having provision for adjusting independently the brake shoes to compensate for wear and to locate the brake shoes properly with relation to the brake wheel.

2. A tension device for sewing machines, having in combination, a tension wheel, a brake for the tension wheel, comprising a brake wheel, a pair of brake shoes for engagement with the periphery of the brake wheel, means for pressing the brake shoes

against the brake wheel, mechanism for moving the brake shoes away from the brake wheel to release the tension and means whereby the brake shoes may be adjusted to cause said mechanism to act uniformly thereon.

3. A tension device for sewing machines, having in combination, a tension wheel, a brake for the tension wheel comprising a pair of brake shoes for engagement with the periphery of the brake wheel, means for pressing the brake shoes against the brake wheel, a device for engagement between adjacent ends of the brake shoes, means for actuating said device to move the brake shoes away from the brake wheel and means whereby the brake shoes may be adjusted with relation to said device.

4. A tension device for sewing machines, having in combination, a tension wheel, a brake for the tension wheel comprising a brake wheel, a pair of brake shoes for engagement with the periphery of the brake wheel, mean for pressing the brake shoes against the brake wheel, a pivoted block for engagement between adjacent ends of the brake shoes and means for rotating the block to disengage the brake shoes from the brake wheel.

5. A tension device for sewing machines having in combination, a tension wheel, a circular casing surrounding and concentric with the tension wheel, a brake for the tension wheel located outside of the casing and means for heating the casing.

6. A tension device for sewing machines, having in combination a tension wheel, a circular casing surrounding and concentric with the tension wheel a brake for the tension wheel located outside of the casing and a steam chest attached to a wall of the casing.

7. A tension device for sewing machines, having in combination, a tension wheel, a circular casing surrounding and concentric with the tension wheel, a tube attached to the casing through which the thread passes on its way to the tension wheel, a tube connected with the casing through which the thread passes on its way from the tension wheel, and means for heating the casing.

8. A tension device for sewing machines having, in combination, a tension wheel, a circular casing surrounding and concentric with the tension wheel, means for heating the casing, a brake for the tension wheel comprising a brake wheel located outside of the casing, and a brake shoe engaging the brake wheel.

WILLIAM C. MEYER.
